UNITED STATES PATENT OFFICE.

BERNARD STEMBER, OF NEW YORK, N. Y.

DESIGN FOR LEATHER OR SIMILAR ARTICLE.

Application filed May 14, 1928. Serial No. 26,657. Term of patent 3½ years.

To all whom it may concern:

Be it known that I, BERNARD STEMBER, a citizen of the United States, residing at New York, in the county of New York, State of New York, have invented a new, original, and ornamental Design for Leather or Similar Article, of which the following is a specification, reference being made to the accompanying drawing, forming a part thereof.

The drawing shows a piece of leather or similar article embodying the design, which comprises arcuate sections blending into a substantially straight section, and which when repeated, show a continuous series of arcuate sections intermediate the straight sections.

I claim:

The ornamental design for leather or similar article, as shown and described.

BERNARD STEMBER.
